United States Patent Office

Des. 193,064
Patented June 19, 1962

193,064

GRAVY BOAT

William T. Jones, Scranton, Pa., assignor to Consolidated Molded Products Corporation, Scranton, Pa., a corporation of Delaware

Filed Nov. 10, 1961, Ser. No. 67,460

Term of patent 14 years

(Cl. D44—21)

FIG. 1.

FIG. 2.

FIG. 3.

FIG. 1 is a perspective view of a gravy boat showing my new design;

FIG. 2 is a front end elevational view thereof; and FIG. 3 is a rear end elevational view thereof.

I claim:

The ornamental design for a gravy boat, as shown.
